(57) **CLAIM**

The ornamental design for a "lamp for aquariums," as shown and described.

DESCRIPTION

FIG. 1 is a front, top, and left side perspective view showing my new design for a lamp for aquariums.

FIG. 2 is a top view of the lamp for aquariums shown in FIG. 1.

FIG. 3 is a bottom view of the lamp for aquariums shown in FIG. 1.

FIG. 4 is a front view of the lamp for aquariums shown in FIG. 1.

FIG. 5 is a rear view of the lamp for aquariums shown in FIG. 1.

FIG. 6 is a left side view of the lamp for aquariums shown in FIG. 1.

FIG. 7 is a right side view of the lamp for aquariums shown in FIG. 1; and,

FIG. 8 is a bottom and right side perspective view of the lamp for aquariums shown in FIG. 1.

The subject matter shown in dashed lines represents environment only and forms no part of the claimed design.
